UNITED STATES PATENT OFFICE.

MAURICE J. WALSH, OF NEW YORK, N. Y.

APPARATUS FOR STOWING CARGOES IN VESSELS.

SPECIFICATION forming part of Letters Patent No. 254,740, dated March 7, 1882.

Application filed April 21, 1880. Renewed February 2, 1882. (Model.)

To all whom it may concern:

Be it known that I, MAURICE J. WALSH, of the city of New York, in the county and State of New York, have invented certain new and 5 useful Improvements in Apparatus for Stowing Cargoes in Vessels, of which the following is a specification.

My invention is adapted to be used in connection with hydraulic jacks for which were 10 granted United States Letters Patent dated October 3, 1876; and its object is to provide for conveniently operating a series of such jacks upon a dock for stowing cotton or other cargo in vessels.

15 One of my improvements consists in the combination, with a jack and its supply-pipe, of a waste-pipe extending from said jack and surrounding the supply-pipe, whereby the supply-pipe is stayed and its liability to burst from 20 excess of pressure is lessened, and in case of rupture the water is confined in the outer waste-pipe and the wetting of the cargo prevented.

Another improvement consists in the combination, with a dock, of a line supply-pipe extending along the same for supplying a motive 25 agent to a series of jacks, a line waste-pipe also extending along the dock for receiving the exhaust from said jacks, and a series of jacks 30 connected with said pipes by flexible hose-connections, and preferably, also, an accumulator and pump for maintaining a uniform pressure in said supply-pipe.

Another improvement consists in the combination, with a dock, of line supply and waste 35 pipes extending along the same for operating a series of jacks, a pump connected with said supply-pipe for supplying a motive agent thereto, and a second pump connected with 40 said waste-pipe for exhausting a motive agent therefrom, whereby provision is afforded for withdrawing all water from the jacks at night to prevent freezing in cold weather.

Another improvement consists in the combination, with a jack and its supply-pipe, of 45 the exhaust-pipe surrounding the supply-pipe, and a novel construction of valve for regulating the flow of water to the jack.

Other improvements consist in details of 50 construction and combinations of parts to be hereinafter fully explained.

In the accompanying drawings, Figure 1 represents a plan of a dock having my improved apparatus arranged upon it. Fig. 2 represents an elevation of an accumulator embodying my invention. Fig. 3 represents a central vertical section on the dotted line *xx*, Fig. 2. Fig. 4 represents a horizontal section of said accumulator on the dotted lines *yy*, Fig. 2. Fig. 5 represents a section of a portion of a 60 jack and a valve for regulating the supply of water to the jack; and Fig. 6 represents a similar section, only showing the valve in a different position.

Similar letters of reference designate corresponding parts in all the figures.

A designates a dock at which vessels may be loaded, and *B* designates a pipe extending along the dock, in the present instance upon three sides thereof. The pipe *B* constitutes a 70 line supply-pipe for operating hydraulic jacks *C*, any number of which may be connected with it at different points by means of flexible pipes or hose.

Extending parallel with the pipe *B* is a second line-pipe, *E*, which may be of somewhat larger diameter than the pipe *B*, and serves the purpose of a discharge or exhaust pipe for the jacks *C*.

Placed at intervals along the line of the exhaust or discharge pipe *E*, and connected therewith by means of branches *a*, are couplings or *T*-pieces *b*, to which the exhaust or discharge pipes *D* are connected, and through each coupling or *T*-piece there extends a branch pipe, *c*, 85 leading from the line supply-pipe *B*. To the pipe *c* is attached a hose, *d*, of smaller diameter than the hose *D*, and constituting the supply-pipe for the jacks. In Fig. 4 is represented an enlarged view of one of these coupling or *T*-pieces, and from it the arrangement of the pipes can be clearly understood. A heavy pressure is used for operating the jacks, and as the supply-hose is surrounded by the exhaust or discharge hose it is supported or 90 stayed, and in case of breakage the water will not escape over the cargo and injure it, but will be confined within the discharge-pipe *D*.

F designates a diagram view of a vessel loading at its dock, and jacks connected by the 95 flexible pipes *D* *d* may be carried to all parts of the vessel for stowing cargo.

In order to provide for the return of the plungers or pistons C' of the jacks C, I employ a slide-valve, C², arranged upon the side of the jack, and working between two seats, r' r'. In 5 the seat r' are ports s, which communicate one with each end of the jack. In the seat r is an annular port, t, which is in communication with the exhaust or discharge pipe D, and a port, u, which is in communication with the supply 10 pipe d. The ports v through the valve itself are always in communication with the ports s, and by moving the valve longitudinally the said ports v in the valve are alternately brought in communication with the annular 15 exhaust-port t and the supply-port u. By this means the water can be alternately supplied to and exhausted from each end of the jack, and the plunger or piston thereof operated.

In order to maintain a uniform pressure upon 20 the supply-pipe B, whether one or a number of jacks are in operation, I employ an accumulator, G, with which the supply-pipe B is connected by the branch pipe e; and H designates a pump for maintaining a pressure in the accumulator 25 and supply-pipe. The water-cylinders f of the pump are surrounded by a tank, g, with which the discharge or exhaust pipe E is connected, and h designates the steam-cylinder for operating the pump. The steam-cylinder h of said 30 pump receives steam through a pipe, i, from a boiler, A', and the water-cylinders are connected by a discharge-pipe, j, with the branch pipe e, as clearly illustrated in Fig. 1.

Figs. 2, 3, and 4 clearly represent the accumulator, which, as represented, consists of a 35 cylinder, I, fitted with a piston, J, and piston-rod J', which works through a packing or stuffing box, I', at the top of the cylinder. The branch pipe e communicates with a port, k, 40 which communicates with the cylinder below the piston. As the water is forced into the accumulator the piston J is raised, and with it the cross-head J², attached to the piston-rod J'.

In the cross-head J² are fixed pulleys or 45 sheaves J³ J⁴, and in the frame-work at the bottom of the accumulator are fixed stationary pulleys or sheaves J⁵.

K designates the frame-work of the accumulator, and at the top thereof are fixed other 50 stationary pulleys or sheaves, J⁶.

L designates ropes or tackle, one end of which is fixed at l, and which passes first over the pulleys or sheaves J³, thence downward around the pulleys or sheaves J⁵, and up and 55 down around the pulleys J⁴ and J⁶, thence upward over the pulleys or sheaves J⁶, and provided at their ends with weights M, which slide in guides or ways m in the frame-work K. As the piston is raised the cross-head, with its 60 sheaves, is moved upward, and extending the ropes L raises the weights M, which exert a constant pressure on the water in the accumulator.

When only one or a small number of jacks 65 are in use the capacity of the pump H is greater than is required, and the surplus water is discharged into the accumulator, while when a

large number of jacks are in use the capacity of the pump is inadequate to furnish the supply, and the deficit is furnished by the accumulator. This arrangement enables the pressure of the supply to be kept uniform, thereby 70 enabling more effective work to be done, and preventing sudden increase of pressure, which strains and ultimately bursts the flexible hose 75 to which the jacks are connected.

The particular construction of the accumulator here shown forms no part of my present application, but may be made the subject of another application for Letters Patent. 80

In the supply-pipes B, leading from the accumulator, are valves n, for shutting the water-supply from either side of the dock. In order to exhaust the jacks of water, it is necessary to create a suction on the discharge-pipes 85 E, and N designates a pump which is attached to said discharge-pipes and draws the water from them, discharging it through a pipe, o, into the tank g, surrounding the water-cylinder f of the pump H. This pump may be supplied 90 with steam through a pipe, p, from the boiler A'.

As the line supply and discharge pipes B and E are very much exposed to the weather, there is great liability of the water in them freezing, and to obviate this I employ a pipe, 95 O, extending in proximity to them, in this instance between them, and adapted to receive a heating agent—such as steam. In the present instance the steam is supplied by a pipe, O', from a boiler, O², and after passing through 100 the pipe O is exhausted into the tank g, still further heating the water.

The several pipes B, E, and O are intended to be boxed up, so as to confine the heat radiating from the pipe O and effectually prevent 105 freezing.

P designates a cotton-press, of any ordinary construction, arranged within the dock A, but supported upon a separate and independent foundation. This press, as here represented, is 110 intended to operate by steam, which may be supplied to it by a pipe, O³, from the boiler O². As the foundation for the press is built very strongly and is surrounded by the dock, it serves to greatly strengthen the latter, and by 115 bracing the dock from the said press-foundation its power to resist the action of the waves and its durability are greatly increased.

The combination and arrangement of my apparatus effects a great saving in stowing cargo 120 of various kinds in vessels, and for stowing cotton in the hold of a vessel it possesses many advantages in addition to those heretofore mentioned. A vessel loaded with cotton can discharge her cargo at the dock, when it 125 is compressed, without removal or unnecessary expense, and again loaded with the compressed bales in very much less time than by the old system of loading cotton, and as vessels are under heavy expense while in port this saving 130 of time is of the greatest importance.

What I claim as my invention, and desire to secure by Letters Patent, is—

1. The combination, with a jack and its sup-

ply-pipe, of a waste-pipe extending from said jack and surrounding the supply - pipe, substantially as specified.

2. The combination, with a dock, of a line supply-pipe extending along the same for supplying a motive agent to a series of jacks, a line waste-pipe also extending along the dock for receiving the exhaust from said jacks, and a series of jacks connected with the said pipes by flexible hose-connections, substantially as specified.

3. The combination, with a dock, of a line supply and a line waste pipe extending along the same, a series of couplings or T-pieces connected to said waste-pipe by branch connections, flexible supply-pipes extending through said couplings and connected to a series of jacks, and flexible exhaust-pipes connecting said jacks with said couplings, and surrounding the flexible supply-pipes, substantially as specified.

4. The combination, with a dock, of line supply and waste pipes extending along the same,

a pump for supplying a motive agent to said supply-pipe, an accumulator for maintaining a uniform pressure in said supply-pipe, and a series of jacks connected with said supply and waste pipes by flexible hose-connections, substantially as specified.

5. The combination, with a dock, of line supply and waste pipes extending along the same for operating a series of jacks, a pump connected with said supply-pipe for supplying a motive agent thereto, and a second pipe connected with said waste-pipe for exhausting the motive agent therefrom, substantially as specified.

6. The combination, with a jack and its supply and exhaust pipes, the exhaust-pipe surrounding the supply-pipe, of the valve C², for controlling the operation of the jack, substantially as specified.
